UNITED STATES PATENT OFFICE.

GEORGE S. HILL, OF BRADFORD, MASSACHUSETTS, ASSIGNOR TO HILL MOTOR CAR COMPANY, OF HAVERHILL, MASSACHUSETTS, A CORPORATION OF MAINE.

STEERING-GEAR FOR AUTOMOBILES.

No. 927,143.

Specification of Letters Patent.

Patented July 6, 1909.

Application filed November 20, 1905. Serial No. 288,226.

To all whom it may concern:

Be it known that I, GEORGE S. HILL, of Bradford, in the county of Essex and State of Massachusetts, have invented certain new and useful Improvements in Steering-Gear for Automobiles, of which the following is a specification.

This invention relates to the steering mechanism of auto-vehicles, and particularly to that portion of the mechanism including and immediately adjacent to the steering post, which is usually supplied with a hand wheel.

The object of the invention is to provide a light, yet strong and simple mechanism to obtain increased steering movement with a minimum of hand movement.

A further object is to provide improved means for holding the steering wheels of the vehicle locked until positively turned so as to avoid any possibility of accidental turning movement.

A further object is to provide an improved construction of the casing to contain oil in which the gear is immersed.

To these ends the invention consists in the construction and combination of parts substantially as hereinafter described and claimed.

Of the accompanying drawings,—Figure 1 represents a longitudinal section through a post and gear embodying the invention. Fig. 2 represents a side elevation of the same, omitting the hand wheel. Fig. 3 represents a section on line 3—3 of Fig. 1. Fig. 4 represents an elevation on a reduced scale, showing the device in the position which it occupies relatively to a vehicle body, said figure also showing one steering wheel.

The same reference characters indicate the same parts in all the figures.

The lower and upper parts of the casing are represented respectively at 10 and 11, said parts having flanges connected by suitable bolts 12. The lower part of the casing is provided with a bracket 13 which preferably extends upward, as indicated in Fig. 2, and is formed with a vertical face or end 14, by means of which the entire casing and the steering gear supported thereby may be attached to a suitable part of the frame of the machine.

The upper part 11 of the casing is formed with a tube extension 15 in which is mounted a hollow or tubular steering post 16 having a

hand wheel 17 of an ordinary form. Keved to the lower end of the post 16 is a sleeve 18, said sleeve being practically a portion of the tubular steering post. The sleeve 18 is formed with an upper thread 19 and a lower 60 thread 20 (see Fig. 1), one of said threads being right-hand and the other left-hand. Fitting the upper thread 19 is a nut 21, hereinafter referred to as the rack nut, said nut being formed with rack teeth 22 and with a 65 key or feather 23 fitting between guiding ribs 26 projecting inward from a plate 24, the latter being connected to the casing by screws 25. It will now be understood that, when the post 16 and sleeve 18 are rotated 70 and either held from longitudinal movement or limited in such movement, the rack nut 21 becomes a longitudinally sliding member, since the coöperation of the feather 23 and guiding ribs 26 prevents said nut from 75 rotating.

The rack 22 of the longitudinally sliding member or nut 21 engages the teeth of a segment 27 formed on a hub 28 which is secured to a rock-shaft 29 mounted in bearings 30, said rock-shaft having an arm 31 secured thereto by means such as a binding nut 32, shown in Fig. 3. The end of the arm 31 is provided with a pin 33 having a spherical shaped end which is connected by 80 a link 34 with an arm or lever 35 forming a portion of the mechanism which turns the steering wheels 36 on their usual vertical pivots. As the construction of the pivots on which the steering gears are mounted is 85 well known and forms no part of the present invention, further illustration or description thereof is unnecessary. As will be readily understood, the steering member operated through the link 34 might be a device other 90 than a wheel, as for instance, the rudder of a motor boat.

A portion of the frame of the vehicle is represented at 37 in Fig. 4.

With the construction so far described, 100 the rotation of the steering post would effect movement of the steering device only to such a degree as would be caused by the longitudinal movement of the rack nut 21, if the post itself had no longitudinal movement. 105 To increase the movement that would be imparted to the steering device, I provide a construction which causes the steering post to move endwise when rotated. To this end an internally-threaded shell 38 is secured in 110

the lower part 10 of the casing, and in effect, forms a stationary nut engaging the lower threads 20 of the sleeve 18. Of course the stationary shell or nut 38 is threaded to correspond with the threads 20, and since the direction of the thread 20 is opposite to that of the thread 19, the movement of the longitudinally sliding member or nut 21 relatively to the stationary nut 38 will be doubled when 10 the hand wheel 17 and post 16 are rotated. At the same time, the connections provide means which would prevent any accidental movement of the steering device, since the pitch of the threads is such that no strain 15 is exerted upon the arm 31 of the rock-shaft could operate through the segment 27 to shift either the longitudinally sliding member 21 or the steering post endwise. As will be readily understood, the steering post, by 20 having its lower end carried by a fixed part, such as the nut 38, in addition to the support afforded by the extension 15, will be held firmly against any movement other than the longitudinal movement hereinbefore described, the widely separated position of 25 these supports preventing any tendency to a rocking of the post with a resultant liability of damage to the post and the mechanism operated thereby.

30 Secured to the lower end of the casing member 10 is a bottom cap 39 having a central opening in which is secured the lower end of a tube 40, the latter projecting upward preferably to a point above the horizontal plane of the intermeshing movable parts of the gearing. Said tube serves to guide and protect the usual connections for controlling the spark timer of the motor, and at the same time prevents the escape of any oil 35 through the opening of the bottom cap. When the parts are being assembled, and before the two parts of the casing and the plate 24 are completely put together, the casing is supplied with as much oil as it will 40 contain so that at least the lower portion of the gearing will be immersed in oil. The level of the oil need not be above the upper thread 19 because the longitudinal movements of the steering post and its sleeve 18, 45 and the rack nut 21, will cause the oil to be transmitted to a point sufficiently high to keep the parts well lubricated.

50 As above stated, the tubular post enables the spark-timing connections to be led through it. Owing to the fact that the tubular post is supported at two separated positions, one above and the other below the point where power is communicated to the steering gear, the said tubular post can 55 be made of quite light material; that is, the sleeve 18, or lower portion of the post, does not require to be made of such heavy or strong material as would be necessary if it had but one bearing.

60 65 It will be observed that if it should be de-

sired to obtain access to the gearing in the casing for such purposes as cleaning the same, the removal of the bolts 12 and the screws 25 which connect the plate 24 with the upper part of the casing, will enable said 70 upper part of the casing and its tube extension 15 to be slid upward on the post 16 where they may remain or be held during the cleaning or examination of the gearing.

I claim:

1. A steering gear comprising a tubular post having oppositely-threaded sections, a casing having an internally-threaded shell or nut fixed therein and engaging one of the threads of said post, a nut engaging the other thread of the post and having means whereby it is prevented from rotating, said casing and fixed nut supporting the post against a rocking movement, and steering connections operated by said nut. 85

2. A steering gear comprising a tubular post having oppositely-threaded sections, a casing having an internally-threaded shell or nut fixed therein and engaging one of the threads of said post, the engagement of the nut and post being at the lower end of the latter, a nut engaging the other thread of the post and having means whereby it is prevented from rotating, a support for the post carried by said casing above said nuts, and steering connections operated by said non-rotating nut. 90

3. A steering gear comprising a post having oppositely-threaded sections, a casing having an internally-threaded shell or nut fixed therein and engaging one of the threads of said post, a nut engaging the other thread of the post having rack teeth and provided with means for preventing its rotation, a toothed segment engaging said rack teeth, 100 and connections between said toothed segment and the steering member of a vehicle. 105

4. An automobile steering gear comprising a two-part shell or casing, a nut fixed therein, a steering post having a threaded portion engaging said nut and having another portion threaded in a direction opposite thereto, a rack nut fitting the last-mentioned thread of the post and having means engaging the casing to prevent rotation of 110 said nut, a toothed segment engaging the rack of said nut, and connections between said segment and the steering member of a vehicle. 115

5. An automobile steering gear comprising 120 an upwardly extending two-part casing, the lower member of said casing having a bracket or arm extending therefrom and terminating in a vertical end face for connecting it to the frame of a vehicle, a steering post mounted in said casing in a manner to permit longitudinal movement therein, a rock-shaft also mounted in said casing, and gearing located in said casing for transmitting motion from the post to said rock-shaft. 125

6. A steering mechanism comprising a casing having a fixed nut and a movable nut, said casing inclosing the movable nut and screws and provided with a lengthwise guide for the movable nut, screws of opposite pitch each engaging one of the nuts, a rock arm actuated by the movable nut, and a steering post for rotating the screws. 5
7. A steering mechanism for self-propelled vehicles comprising a steering post, a right and left hand screws rigid on the post, a casing having a fixed nut engaging one of the screws, an axially movable nut engaging the other screw, said casing inclosing the movable 10 nut and screws and provided with a lengthwise guide for the movable nut, and a shifting element actuated by the axially movable nut. 15
8. A steering mechanism for self-propelled vehicles, comprising a steering post, screws rigidly mounted end to end upon the post, a fixed threaded part engaged with one of the screws and an axially movable threaded part engaging the other screw, a fixed casing inclosing said screws and axially movable 20 threaded part and provided with a lengthwise guide for said axially movable threaded part, an oscillatory element actuated by the last named threaded part and a shifting element rigid with the oscillatory element. 25
- In testimony whereof I have affixed my signature, in presence of two witnesses.
